[57] CLAIM

The ornamental design for a golf practice device, as shown and described.

DESCRIPTION

FIG. 1 is a perspective view of a golf practice device showing our new design;

FIG. 2 is an enlarged top plan view thereof;

FIG. 3 is a front elevational view of FIG. 2;

FIG. 4 is a right side elevational view of FIG. 2;

FIG. 5 is a left side elevational view of FIG. 2;

FIG. 6 is a rear elevational view of FIG. 2; and,

FIG. 7 is a perspective view of FIG. 2.

The item shown in phantom lines depicts the environment of our new design and forms no part of the design of our invention.
